UNITED STATES PATENT OFFICE.

FREDERICK A. WEIDMAN, OF THOMASTON, CONNECTICUT, ASSIGNOR TO SETH THOMAS CLOCK CO., OF THOMASTON, CONNECTICUT, A CORPORATION.

DESIGN FOR A CLOCK CASE.

Application filed July 25, 1925. Serial No. 14,207. Term of patent 3½ years.

To all whom it may concern:

Be it known that I, FREDERICK A. WEIDMAN, a citizen of the United States, residing at Thomaston, in the county of Litchfield and State of Connecticut, have invented a new, original, and ornamental Design for a Clock Case, of which the following is a specification, reference being had to the accompanying drawing, forming part thereof.

I claim:

The ornamental design for a clock case as shown.

FREDERICK A. WEIDMAN.
